TABLE

Melbourne F. Smith, Jr., Lenoir, N.C., assignor to Broyhill Furniture Factories, Lenoir, N.C., a partnership

Filed Apr. 15, 1963, Ser. No. 74,422

Term of patent 14 years

(Cl. D33—14)

The dominant features of my design reside in those portions shown in full solid lines on the drawings.

I claim:

The ornamental design for a table, substantially as shown and described.
